UNITED STATES PATENT OFFICE.

HARRISON V. CONWAY, OF BOONE, IOWA.

COMBINED HARROW, SEEDER, AND MOWER.

SPECIFICATION forming part of Letters Patent No. 445,543, dated February 3, 1891.

Application filed April 3, 1890. Serial No. 346,446. (No model.)

To all whom it may concern:

Be it known that I, HARRISON V. CONWAY, a citizen of the United States, residing at Boone, in the county of Boone and State of Iowa, have invented a new and useful Combined Harrow, Seeder, and Mower, of which the following is a specification.

This invention has relation to agricultural machines, and among the objects in view are to combine three important machines in one structure—namely, a harrow, a seeder, and a mower; to provide means for conjointly or separately operating all or each, as desirable, and this in a simple and convenient manner, all as will hereinafter appear, and be particularly pointed out in the claims.

Referring to the drawings, Figure 1 is a plan of a combination agricultural machine constructed in accordance with my invention. Fig. 2 is a vertical longitudinal section. Fig. 3 is a side elevation. Fig. 4 is a detail in perspective of the harrow. Fig. 5 is a detail in front elevation of the cutter-bar connecting and operating mechanism.

Like numerals of reference indicate like parts in all the figures of the drawings.

1 represents an oblong frame provided with opposite bearing-boxes 2, in which is mounted a transverse axle 3, provided outside of the frame with ground-wheels 4 of the usual construction. Mounted upon the axle 3 is a master-gear 5, fixed to the axle and adapted to revolve therewith. The ground-wheels are loose upon the axle, and between said wheels and the frame-work at each side of the latter there is mounted a fixed ratchet-wheel 6. The wheels are provided upon their inner sides with pivoted pawls 7, pressed into mesh with their respective ratchet by means of springs 8, secured to the wheels. The teeth of the ratchets are disposed to the rear, so that the pawls are in engagement with the teeth only when the machine moves forward, and therefore only turns the axle at that time, and in backing said pawls ride over the teeth of their ratchets and the axle remains inactive.

At one side of the oblong frame and underneath the same there is arranged a pair of bearing-brackets 9. Opposite each other and mounted for rotation therein is a shaft

10, having a small pinion 11 meshing with the main gear and adapted to be driven thereby. The shaft is also so arranged in the bearings as to be adapted for longitudinal movement 55 therein, so that the pinion may be withdrawn from mesh or engagement with the large gear, which is accomplished by means of a hand-lever 12, loosely engaging the shaft and pivoted, as at 13, to a standard 14, projecting up 60 from the frame and provided with opposite locking-notches 15, the handle of the lever being within ready grasp of a person occupying the driver's seat 16, which is supported by a rearwardly - disposed spring - standard 17, 65 mounted upon a longitudinal beam 18. The forward end of the shaft 10 is provided with a crank-disk 19, having a crank-pin 20, and loosely connected with the pin is a connecting-rod 21, the opposite end of which loosely 70 engages the upper end of a bell-crank 22, pivoted to a bracket 23, mounted upon an arm 24, depending from the under and adjacent side of the frame-work. An arm 25 is secured at its upper end to the frame-work 75 and to the bracket aforesaid, said arm depending from the frame and extending to one side thereof and pivotally connected, as at 26, between two perforated ears 27, formed at the inner end of a finger-bar 28 of a reaper. 80 Mounted over the finger-bar is a cutter-bar 29, terminating at its inner end in an eye 30, which eye is connected with the lower end of the bell-crank by means of a connecting-rod 31, so that a reciprocatory motion is given 85 the cutter-bar by means of the connecting-rods, the bell-crank, the crank-disk, its shaft 10, and pinion 11, which motion may be stopped by a shifting of the shaft 10 through the medium of the lever controlling the same. 90

Projecting rearwardly from the oblong frame at opposite sides is a pair of bars 32, above which there is supported a transversely-located seed-box 33, the bottom of which is perforated and covered by a seed-slide 34, having perforations adapted to be thrown more or less into registry with the perforations in the box or entirely out of such registry, as occasion may require, and for the purpose of increasing or diminishing 100 or entirely cutting off the feed of seed. A pair of lugs 35 depend from the box near op-

- posite ends, which lugs straddle the rear ends of the rearwardly-projecting bars, the bars and lugs being perforated and locked in removable position by means of removable pins 36, inserted through the perforations.
- 37 represents a Y-shaped arm, the rear end of which terminates in a hook 38 and the forward ends of which are perforated, as at 39, and removably and pivotally connected to 10 the rear ends of the bars 32 by means of opposite pins 38^a. The Y-shaped arm is also provided near its rear end with an eye 39^a, connected with which is a curved rod 40, the forward end of the rod connecting with a 15 hand-lever 41, pivoted to the longitudinal central bar of the frame and adapted to interlock with any one of a series of notches 43, formed in a locking-segment 44. By operating the lever 41 upon its pivot it is apparent that the Y-shaped arm may be raised and lowered upon its pivots.
- 45 represents opposite harrow-sections loosely connected at their front and rear ends by opposite connecting-bridles 46, provided at their 20 centers with upwardly-disposed eyes 47, the rear eye engaging the hook of the Y-shaped arm, and said sections are also connected by a loose connecting-rod 48. The inner longitudinal bars of the harrow-sections are connected loosely at their front ends to draft-rods 47^a, which rods are removably connected with a pair of hooks 48^a, depending from the opposite under sides of the main frame. A pair of brackets 49, provided with bearings, 25 is secured to the under side of the frame 1, and in the same there is mounted for longitudinal and rotary movement a shaft 49^a, provided near its inner end with a small pinion 50, adapted for mesh with the main gear, and 30 near its center provided with a crank portion 51. A lever 52 has its lower end in engagement with the shaft, and is pivoted near its upper end, which projects vertically through the frame, to a standard 53, as at 54, said 35 standard being provided with a pair of locking-notches 55, into which the lever is adapted to take for the purpose of reciprocating the shaft, and thus throw the pinion into and out of mesh with the gear.
- 50 57 represents an oscillating lever pivoted, as at 58, to the under side of the longitudinal beam of the frame and depending under the frame and having its rear end extending beyond the same and terminating in a hooked portion 58^a, loosely engaging the eye of the 40 front bridle of the harrow. A keeper 59 supports the rear end of the oscillating lever, and said lever is connected by a stud 60 with the seed-slide of the seed box or hopper, so that 45 any oscillation of the lever is imparted to the seed-slide and to the front ends of the harrow-sections, whereby said harrow-sections are caused to move over a zigzag course, and thus thoroughly pulverize the soil. The motion given the lever is secured by a connecting-link 61, one end of which is connected with the lever and the opposite end of which is

loosely connected with the cranked portion of the shaft 49.

62 represents the tongue or draft-bar bolted, 70 as at 63, to the front end of the frame and having its rear end terminating under and bolted to the front end of the central longitudinal beam, as at 64, which beam is supported at its front end upon a transverse bolster 65, the 75 ends of which rest upon the sides of the oblong frame 1.

From the above description it will be apparent that the harrow and seeder may be employed in conjunction with each other 80 and the reaping mechanism removed by the withdrawal of the coupling-pin which connects the same with the outer end of the transverse arm and disconnecting the connecting-rod which connects the cutter-bar 85 with the lower end of the bell-crank. When this is accomplished, the lever which governs the shaft 10 is so manipulated as to throw the pinion 11 out of mesh with the master-gear. This lever may be also used when approaching or leaving the field.

If desired, the seed box or hopper may be removed and simply the harrow used, and said harrow by manipulation of its governing-lever may be made to travel in a straight 95 line or zigzag, as desired, or, furthermore, by means of the pivoted Y-shaped arm, the curved rod, and the lever to which it is connected said harrow may be swung upward out of contact with the ground or may be 100 wholly detached with the seed-box or without the same and the mowing mechanism alone used. Whether used combined or separate, the machines are complete and efficient and all may be conveniently operated by a 105 set of levers arranged within easy grasp of the hand of the operator.

A lever 67 is pivoted, as at 68, to one of the side bars of the frame and is provided with a lock or spring-bolt 69, adapted to engage a 110 toothed sector 70.

71 represents a curved bar, one end of which is connected to the lever 67 and the opposite end loosely connected to an eye 72, located upon the reaper. By means of the lever 67 115 the finger and cutter bars may be elevated above the ground and the lever 12 operated to stop the motion of said mechanism.

Having thus described my invention, what I claim is—

1. In a machine of the class described, the combination, with a frame-work, its supporting-axle and ground-wheels, and a master-gear mounted on the axle, of bearings located under the frame, a reciprocating rotatable 125 shaft mounted in the bearings, a lever for reciprocating the shaft, a pinion mounted on the shaft and adapted to be thrown into and out of mesh with the master-gear, a crank-disk mounted on the end of the shaft, a pivoted bell-crank lever, a rod connecting the same with the crank-disk, a depending lateral arm, a bracket for supporting the arm and bell-crank, said arm being adapted to 130

receive and form detachable connection with a finger-bar, and a rod removably connected to the lower end of the bell-crank and adapted for removable connection with the cutter-bar, substantially as specified.

5 2. In a machine of the class described, the combination, with the frame, the rotatable axle, the ground-wheels thereon, and the master-gear rigid therewith, of brackets secured to the frame, a longitudinally-disposed shaft mounted for rotatable and longitudinal movement in the brackets, a lever for operating the shaft, a pinion mounted on the shaft and meshing with the master-gear, a crank-disk 10 secured to the end of the shaft and having a crank-pin, a pivoted bell-crank and brackets for the same, a rod connecting the upper end of the bell-crank with the crank-pin, a transversely-extending arm, a finger-bar of a mowing-machine, having opposite perforated lugs, a removable pin inserted through the lugs and through an eye in the arm, a cutter mounted on the finger-bar, and a rod pivotally connected with the cutter-bar and removably connected 15 with the lower end of the bell-crank, substantially as specified.

3. In a machine of the class described, the combination, with a main frame, a revolute axle, ground-wheels mounted thereon, and a master-gear rigid with the axle, of a vibrating arm pivoted to the main frame, extending to the rear, a crank-shaft mounted in brackets and provided with a pinion meshing with the master-gear, and a link connecting the crank-shaft with the vibratory arm, said main frame and vibrating arm being adapted for loose connection with the harrow-frame, substantially as specified.

4. In a machine of the class described, the combination, with a main frame adapted to be loosely connected with a harrow, of a revolute axle, ground-wheels mounted thereon, a master-gear rigid therewith, bearings secured to the frame, a crank-shaft mounted for reciprocation in the bearings and provided with a pinion meshing with the master-gear, a vibratory arm pivoted under the main frame, a link connecting the same with the crank of the shaft, said arm terminating at 45 its rear end in a hook adapted for connection with a bridle having an eye by which the harrow-sections are connected and adapted to engage the hook, and a pivoted lever secured in the main frame and having its lower end engaging the crank-shaft and its upper end provided with a lock, substantially as specified.

5. The combination, with the main frame,

the supporting-axle, and the master-gear rigid therewith, of the reciprocating and revolute 60 crank-shaft, a lever for reciprocating the shaft, a pinion mounted on the shaft and engaging the master-gear, a vibrating arm pivoted under the same and connected by a link to the crank-shaft, said main frame being 65 adapted for connection with and loosely suspending a harrow and said lever being adapted for loose connection, the said harrow for agitating the same, and the said frame being also adapted to support a transverse seed-box 70 having a seed-slide, and a post adapted to connect the slide with the arm, substantially as specified.

6. The combination, with the oblong frame having rearwardly-extending side bars, and 75 opposite depending hooks adapted to receive opposite harrow-sections which are provided at their front ends with rods adapted for removably engaging the hooks and at their rear ends with an eye, of a Y-shaped arm pivoted in the ends of the opposite bars by removable pins, a pivoted lever, means for locking the same, and a connecting-rod adapted for connecting the lever with the Y-shaped arm, whereby the latter may be elevated and 80 lowered, substantially as specified.

7. In a machine of the class described, the combination, with the oblong frame, the supporting-axle, the ground-wheels, and the master-gear, of the bearing-brackets located at one 90 side of the gear, the crank-shaft mounted for reciprocation therein, the pivoted vibrating arm terminating at its rear end in a hook, the link connecting the arm with the crank-shaft, said frame being adapted for loose connection with harrow-sections, which latter are provided with opposite eyes into which the arm is adapted for insertion, loose rods adapted for removably connecting the front ends of the harrow-sections with hooks, a 100 Y-shaped arm perforated at its ends, removable pins connecting said ends with the bars in a pivotal manner, the rear end of the Y-shaped arm forming a hook and adapted for engaging the rear eye of the harrows, the 105 lever pivoted to the frame and adapted to lock with the toothed segment, and the connecting-rod pivoted to the lever and to an eye on the rod, substantially as specified.

In testimony that I claim the foregoing as 110 my own I have hereto affixed my signature in presence of two witnesses.

HARRISON V. CONWAY.
